ABSTRACT

Certain substituted or unsubstituted p-alkanoyl toluenes, e.g., p-alkanoyl toluene, are useful as anti-obesity and anti-diabetic agents.

8 Claims, No Drawings

SUBSTITUTED OR UNSUBSTITUTED
P-ALKANOYL TOLUENES AS ANTI-OBESITY AND
ANTI-DIABETIC AGENTS

This application is a continuation-in-part of copending application Ser. No. 445,265, filed Feb. 25, 1974, now abandoned.

This invention relates to the pharmaceutical activity of p-alkanoyl toluenes. More particularly, this invention concerns the use of substituted or unsubstituted p-alkanoyl toluenes in the treatment of obesity and diabetes. The invention also relates to pharmaceutical compositions containing these compounds as an active ingredient thereof.

The active agents with which this invention is concerned may be represented by the following structural formula:

where

R₁ represents hydrogen, halo having an atomic weight of about 19 to 36, and straight chain lower alkoxy, i.e., straight chain alkoxy having 1 to 4 carbon atoms, e.g., methoxy, ethoxy, isopropoxy or the like, and

R₂ and R₃ each independently represent alkyl having 1 or 2 carbon atoms, i.e., methyl or ethyl.

The compounds of formula (I) above are known and may be prepared according to methods disclosed in the literature from known materials. The present invention contemplates only the novel use of such compounds as anti-obesity and anti-diabetic agents.

The compounds of formula (I) are useful because they possess pharmacological activity in animals. In particular, the compounds of formula (I) are useful as anti-obesity agents in the treatment of obesity as indicated by (1) preventing an increase in the blood sugar level in male Wistar rats in groups of 4 which have fasted for 16 hours and then are given an initial dose of 200 milligrams per kilogram of animal body weight of the test compound orally. One hour later, the rats are given 2 grams per kilogram of animal body weight of maltose load. Fifteen minutes after administration of the maltose, the rats are anesthetized with 120 milligrams per kilogram of animal body weight of sodium hexobarbital after which blood is collected via cardiac puncture. The blood samples are placed in an autoanalyzer cup containing 0.1 milliliters of heparin (1,000 units per milliliter). The heparinized blood is used to determine the blood sugar level with an autoanalyzer. The blood sugar content is compared to the control group which receives 0.5% carboxymethyl cellulose and are run concurrently, and by (2) preventing an increase in the blood sugar level in male Wistar rats in groups of 4 which are fasted for 16 hours and then are given an initial dose of 200 milligrams per kilogram of animal

body weight of the test compound orally. One hour later, the rats are given 2.5 grams per kilogram of animal body weight of starch load. Thirty minutes after administration of the starch, the rats are anesthetized with 120 milligrams per kilogram of animal body weight of sodium hexobarbital after which blood is collected via cardiac puncture. The blood samples are placed in an autoanalyzer cup containing 0.1 milliliters of heparin (1,000 units per milliliter). The heparinized blood is used to determine the blood sugar level with an autoanalyzer. The blood sugar content is compared to the control group which receives 0.5% carboxymethyl cellulose and are run concurrently. The blood sugar levels are calculated and compared to the control.

15 The compounds of formula (I) are also useful as juvenile anti-diabetic agents in the treatment of diabetes in adults as indicated by the lowering of blood glucose in 6 to 8-week old male Royal Hart mice weighing 30 to 35 grams which are fasted in groups of 5 for 16 hours and then are given an initial dose of 200 milligrams per kilogram of animal body weight of the compound orally. One and one-half hours later, the mice are given orally 2 grams per kilogram of animal body weight of a glucose challenge. Twenty-five minutes later, the mice 20 are anesthetized with 85 milligrams per kilogram of animal body weight of sodium hexobarbital and 5 minutes later blood is collected via cardiac puncture. The blood samples are placed in an autoanalyzer cup containing 0.025 milliliters of heparin (1,000 units per milliliter); 25 and the samples are capped, shaken, and stored in ice. The glucose content is determined by the autoanalyzer potassium ferric-cyanide N-2b method and are compared with a control group, which receives orally 0.5% carboxymethyl cellulose vehicle and are run concurrently.

30 For such uses, the compounds of formula (I) may be administered orally or parenterally as such or admixed with conventional pharmaceutical carriers. They may be administered orally in such forms as tablets, dispersible powders, capsules, soft gelatin capsules, preferably soft gelatin capsules, and emulsions, and parenterally as emulsions, e.g., a sterile injectable emulsion. The compositions for oral use may contain one or more conventional adjuvants, such as sweetening agents, flavoring agents, coloring agents and preserving agents, in order to provide an elegant and palatable preparation. Tablets may contain the active ingredient in admixture with conventional pharmaceutically acceptable excipients, e.g., inert diluents, such as calcium carbonate, sodium carbonate, lactose, and talc, granulating and disintegrating agents, e.g., starch and alginic acid, binding agents, e.g., starch, gelatin and acacia, lubricating agents, e.g., magnesium stearate, stearic acid and talc, and absorbing agents such as colloidal silicone dioxide. 35 The tablets may be uncoated or coated by known techniques to delay disintegration and absorption in the gastro-intestinal tract and thereby provide a sustained action over a longer period. Similarly, suspensions, and emulsions may contain the active ingredient in admixture with any of the conventional excipients utilized by the preparation of such compositions, e.g., suspending agents such as methylcellulose, tragacanth and sodium alginate; wetting agents such as lecithin, polyoxyethylene stearate and polyoxyethylene sorbitan monooleate; 40 and preservatives such as ethyl-p-hydroxybenzoate. Capsules may contain the active ingredient admixed with an inert solid diluent, e.g., calcium carbonate, calcium phosphate and kaolin. Soft gelatin capsules may 45

contain the active ingredient in admixture with conventional pharmaceutical excipients, e.g., inert carriers such as vegetable oils (soybean oil, corn oil and the like) polyethyleneglycol derivatives or mineral oils. The injectable compositions are formulated as known in the art. These pharmaceutical preparations may contain up to about 90% of the active ingredient in combination with the carrier or adjuvant.

The anti-obesity effective dosage of active ingredient employed for the treatment of obesity and the anti-diabetic effective amount of active ingredient employed in the treatment of diabetes may vary depending on the particular compound employed, the mode of administration and the severity of the condition being treated. However, in general, satisfactory results are obtained for both the hypolipidemia effect and the anti-diabetic effect when the compounds of formula (I) are administered at a daily dosage of from about 1 milligram to about 200 milligrams per kilogram of animal body weight, p.o., preferably given in divided doses two to four times a day, or in sustained release form. For most large mammals, the total daily dosage for both indications is from about 75 to about 1,500 milligrams. Dosage forms suitable for internal use comprise from about 20 to about 750 milligrams of the active compound in intimate admixture with a solid or liquid pharmaceutically acceptable carrier or diluent.

Compounds of formula (I) which can be used as the active ingredient include the following:

- 2-chloro-4-pivaloyl toluene
- 2-methoxy-4-pivaloyl toluene, or
- p-pivaloyl toluene, the latter being especially preferred.

A representative formulation suitable for oral administration is a tablet, capsule or soft gelatin capsule prepared by standard tabletting or encapsulating techniques which contains the following and may be administered 2 to 4 times a day in the treatment of obesity or diabetes.

EXAMPLE 1

Ingredient	Weight (mg.) Capsule
p-pivaloyl toluene	100
tragacanth	—
lactose	300
corn starch	—
talcum	—
magnesium stearate	—
	400 mg.

EXAMPLE 2

Ingredient	tablet	Weight (mg.) capsule	soft gelatin capsule
p-pivaloyl toluene	100	100	100
polyvinylpyrrolidone	15	—	—
lactose	282.5	346	—
corn starch	25	—	—
talcum	15	—	—
colloidal silicon dioxide	50	50	—
magnesium stearate	2.5	—	—
stearic acid	—	4	—
soybean oil	—	—	300
	500 mg.	500 mg.	400 mg.

The following pharmaceutical compositions are formulated with the indicated amount of active agent

using conventional techniques. The injectable emulsion, the oral liquid suspension, and the oral liquid emulsion represent formulations useful as unit doses and may be administered in the treatment of obesity or diabetes. The injectable emulsion is suitable for administration once or twice a day whereas the oral liquid suspension and the oral liquid emulsion is suitably administered 2 to 4 times per day for this purpose.

EXAMPLE 3

Ingredient	Weight (mg.) Oral liquid suspension
p-pivaloyl toluene	100
magnesium aluminum silicate	47.5
flavor	q.s.
color	q.s.
methyl paraben, U.S.P.	4.5
propyl paraben, U.S.P.	1.0
polysorbate 80 (e.g., Tween 80), U.S.P.	5
sorbitol solution, 70%, U.S.P.	2,500
buffer agent to adjust pH for desired stability	q.s.
water	q.s. to 5 ml.

EXAMPLE 4

Ingredient	Weight (mg.) Sterile inject- able emulsion	Weight (mg.) Oral liquid emulsion
p-pivaloyl toluene	200	100
sodium, carboxy methyl- cellulose, U.S.P.	—	12.5
polyvinylpyrrolidone	5	—
benzyl alcohol	0.01	—
sodium chloride	to be adjusted to an isotonic concentration	—
flavor	—	q.s.
color	—	q.s.
methyl paraben, U.S.P.	—	4.5
propyl paraben, U.S.P.	—	1.0
polysorbate 80 (e.g., Tween 80), U.S.P.	1	5
sorbitol solution, 70% U.S.P.	—	2,500
buffer agent to adjust pH for desired stability	q.s.	q.s.
water	for injection q.s. to 1 ml.	q.s. to 5 ml.

The preferred pharmaceutical compositions from the standpoint of preparation and ease of administration are soft gelatin capsules containing from about 100 to 200 milligrams of the active ingredient.

What is claimed is:

1. A method for treating obesity which comprises administering to a mammal in need of said treatment an anti-obesity effective amount of a compound of the formula:

where

5

R_1 represents hydrogen, halo having an atomic weight of about 19 to 36, or straight chain lower alkoxy, and
 R_2 and R_3 each independently represent alkyl having 1 to 2 carbon atoms.

2. The method of claim 1 in which the compound is:

10
5

from about 20 milligrams to about 750 milligrams per unit dosage.

6. A pharmaceutical composition useful as an anti-obesity agent comprising a compound of the formula:

15

where R_1 , R_2 and R_3 are as defined in claim 1, and a pharmaceutically acceptable carrier therefor, said compound being present in an amount of from about 75 milligrams to about 1500 milligrams.

7. The composition of claim 6 in which the active ingredient is p-pivaloyl toluene.

8. The pharmaceutical composition of claim 6 wherein said active ingredient is present in said composition in an amount of from about 20 milligrams to about 750 milligrams per unit dosage.

UNITED STATES PATENT OFFICE
CERTIFICATE OF CORRECTION

Patent No. 3,924,003 Dated Dec. 2, 1975

Inventor(s) Robert S. Ho, William J. Houlihan, Jeffrey Nadelson

It is certified that error appears in the above-identified patent and that said Letters Patent are hereby corrected as shown below:

Col. 3, line 16, please delete the word "hypolipidemia"
and insert in its place the word -- anti-obesity --.
